HIGH-PRESSURE BOILER HAVING A LARGE HEATING SURFACE AND PARTICULARLY ADAPTED FOR LOCOMOTIVES

Hans Nyffenegger, Winterthur, Switzerland, assignor to firm Schweizerische Lokomotiv- und Maschinenfabrik, Winterthur, Switzerland

Application January 4, 1933, Serial No. 650,196, and in Germany January 8, 1932

1 Claim. (Cl. 122—235)

This invention relates to high pressure boilers having a large heating surface and particularly adapted for locomotives.

With high pressure water tube boilers particularly for locomotives, it is known, to arrange the water tubes in fork-shaped evaporating elements that are transversely disposed to the longitudinal axis of the upper steam collecting drum (Fig. 1) in such manner that they ascend from two lower drums extending laterally of the grate, so that the entity of the water tubes form the two side walls of the fire box and the fire box ceiling which protects the upper drum from being heated. The steam generated in every one of the evaporating elements succeeding each other in the longitudinal direction of the boiler is led into the upper drums through a short pipe connection which is welded on to the portion of the element forming the ceiling of the fire box and beaded on to the upper drums.

This arrangement for the evaporating elements provides with the usual pipe dimensions a construction which is adapted to practically compensate the expansions due to heat arising during the operation (which is always the case), so that with different temperatures existing between the drum system, (particularly the supports therefor) and the system of the water or evaporating tubes no detrimental stresses caused by the heat expansions occur. However, the following points must be considered. Owing to the fact that the vertical pipe connections arranged in the horizontal part of the U-shaped pipes are positioned laterally off the centre of the pipe, for the purpose, of providing that the places where the tubes are beaded onto the upper drum are situated on different sides of the longitudinal middle plane of the upper boiler, by an alternate arrangement, the legs of the water tubes are of unequal lengths, whereby dangerous stresses due to heat particularly in the vertical pipe connections on the upper drum arise. When the evaporating elements are made in two pieces of a pipe each of which is separately connected to the upper drum (Fig. 3) the stresses due to heat are practically eliminated which permits of forming the evaporating elements, in the simplest manner, only by bending and without welding.

With boilers of a large heating surface in which at least two upper drums are arranged and, consequently, in the usual constructions to the evaporating elements for each upper drum a separate steam eduction pipe had to be allotted, difficulties arose. In a similar manner as for boilers

including only one upper drum (Fig. 1) each evaporating tube was to be connected by a separate pipe connection to the upper drums, (Fig. 2). The horizontal portion of the evaporating elements provides also here effective protection for the upper drums against heating up, but the portion of the upper drums disposed between the pipe connections may cause extremely dangerous stresses due to heat, particularly in the pipe connections, when differences in the temperatures of the system of carriers for the drums and the water tubes occur.

These stresses may be avoided by providing pipe connections of longer lengths, but with the undesirable consequence that the height of the side walls of the fire box is decreased and a very valuable amount of heating surface is lost. A further disadvantage of the said disposition is that the content in the tubes of the ceiling between the two educting connections and the upper drums may be caused to stagnate even with higher outputs of the boiler, wherefrom dangerous overloading of the boiler may accrue. On the other hand, also from the point of view of manufacturing the boiler this kind of connection to the upper and the lower drums is undesirable.

According to the present invention, the lower drums are alternately connected at each evaporating element with one of the upper drums.

In this manner a continuous ceiling for protecting the upper drums against being heated is formed the small interruptions of which arising between the educting connections can easily be filled out with any suitable fire-proof mass.

This construction may, in a similar manner, also be applied to boilers comprising three or more upper drums.

In the accompanying drawing a constructional form of the invention is schematically illustrated together with several known constructions, in which

Fig. 1 represents a cross section of a boiler of a known construction comprising one upper drum and forked evaporating elements;

Fig. 2 is a cross section of a boiler including two upper drums and forked evaporating elements;

Fig. 3 is a cross section of a boiler comprising one upper drum and bipartite evaporating elements, and

Fig. 4 depicts a cross section of a boiler having two upper drums and bipartite evaporating elements.

Referring to Fig. 1 of the drawing, for a known arrangement, an upper drum *a* is connected

with the lower drums b' , b' through a forked evaporating element c by means of a pipe connection d .

In Fig. 2, which shows another known arrangement 5 two upper drums a , a' are illustrated which are connected with the lower drums b , b' through a forked evaporating element c which is provided with two pipe connections d , d' . f and d , d' denote the parts of the evaporating 10 element e which are subjected to particularly dangerous stresses due to heat;

In Fig. 3, showing still another known arrangement, 15 an upper drum a communicates with a lower drum b by an evaporating tube g and with the lower drum b' by a tube g' . The tubes g and g' lie in the same transverse plane and constitute conjointly one of the evaporating elements.

Fig. 4 illustrates an arrangement according 20 to the present invention. By a , a' two upper drums are designated which alternately communicate with two lower drums b , b' . For this purpose the upper drum a is connected by the water or evaporating tubes g , g' with the lower drums b , b' and the upper drum a' with the lower drums b , b' by the tubes h , h' forming the next succeeding evaporating element. i is the front end wall of the fire box.

In order to prevent undue stressing of the material of the upper drums, the tubes g , g' and h , h' respectively are joined with the upper drums alternately on the right hand side of the vertical longitudinal planes extending through the centre of the upper drums and on the left hand side of these planes.

I do not limit myself to the particular size, shape, number or arrangement of parts as shown and described, all of which may be varied without going beyond the scope of my invention as shown, described and claimed.

What I claim is:

In a high-pressure boiler of the type described, in combination two lower water drums, at least two upper steam collecting drums, a fire box situated between said drums, evaporating tubes extending in pairs of correlated branches from said lower drums to said upper drums in transverse planes perpendicularly disposed to the longitudinal middle plane of the boiler, said branches having vertical portions conjointly constituting the side walls of said fire box and having substantially horizontal portions constituting the ceiling of said fire box for protecting said upper drums against radiating heat from said fire box, said horizontal portions extending with their adjacent ends with only a small interstice between same, for rendering the heat protection by said ceiling effective throughout the extent of the ceiling, separate pipe connections on said adjacent ends of said horizontal portions of said pairs of evaporating tube branches extending up to said upper drums with alternate pairs of correlated pipe connections arranged on a different upper drum in the various transverse planes, and a lower pipe connection on each branch tube extending down to the correlated lower drum in substantially parallel relation to the upper pipe connection of the respective branch tube.
